Attorney*

UNITED STATES PATENT OFFICE

JOSEPH SACHS, OF WEST HARTFORD, CONNECTICUT

INCLOSED FUSED SWITCH

Application filed January 15, 1931. Serial No. 508,943.

The invention relates particularly to an inclosed fused switch having the fuse contacts and the switch parts arranged to be respectively accessible and inaccessible through an opening in the front cover or wall of the inclosing cabinet, having a fuse or auxiliary cover for closing the opening in the front wall and normally preventing access to the fuse contacts, and having interlocking means for preventing opening of the auxiliary cover when the switch is closed and for preventing closing of the switch when the auxiliary cover is open.

One of the objects of the present invention is to provide an improved inclosed fused switch of the type described having an auxiliary cover movable parallelly with the plane of the main cover and adapted to be unlocked as the result of a relatively small lateral movement and then be moved in another direction, preferably vertically, to an open position.

A further object of the invention is to provide certain improved structural features whereby the foregoing major object is attained.

In the accompanying drawings I have shown the embodiment of the invention which I now prefer, but it will be understood that the drawings are intended for illustrative purposes only and are not to be construed as defining or limiting the scope of the invention, the claims forming a part of this specification being relied upon for that purpose.

Of the drawings:

Fig. 1 is a fragmentary front view of an inclosed fused switch embodying the invention.

Fig. 2 is a fragmentary side view of the switch shown in Fig. 1.

Fig. 3 is a view similar to Fig. 1 but showing the parts in different positions.

Fig. 4 is a fragmentary vertical sectional view taken along the line 4—4 of Fig. 1.

Fig. 5 is a fragmentary horizontal sectional view taken along the line 5—5 of Fig. 1.

As concerns the details of the cabinet to which the invention may be applied, I do not narrowly limit myself but in order to clearly illustrate the invention I have shown a cabinet 1 of conventional form having a back wall 2, side walls 3, end walls 4, and a front wall 5. Ordinarily and preferably the front wall 5 is in the form of an openable cover pivoted at 6, 6 to one of the walls 4 as for instance the bottom end wall. The cover may be held in closed position by any usual or preferred means such as a latch. The front wall 5, whether constructed in the form of an openable cover or otherwise, has an opening such as 7 therein.

Mounted within the cabinet is a fused switch mechanism so arranged that the fuse contacts are accessible from the exterior of the cabinet through the opening 7 when the cover 5 is closed and so arranged that the switch parts are inaccessible through the said opening when the cover is closed. The details of the fused switch mechanism may be widely varied and I do not limit myself to a fused switch mechanism of any particular form. However, for the purpose of clearly illustrating the invention I have shown a fused switch of the type disclosed in my patent for electric circuit controlling appliance, No. 1,754,445. The fused switch as shown comprises a base 8 of insulating material which is so mounted within the cabinet as to close the opening 7 in the front cover 5. Carried by the base 8 at 80 the front thereof are pairs of fuse receiving contacts such as 9, 9 these contacts being accessible from the exterior of the cabinet through the opening 7.

The switch mechanism within the cabinet 85 comprises stationary switch contacts 10 and 11 some of which may be electrically connected with the respective fuse contacts 9, 9. In addition to the stationary switch contacts 10 and 11 the switch comprises movable contacts 90

12 and 13 carried by rectilinearly movable insulating elements 14.

There is provided an operating means for the switch mechanism which includes a handle on the exterior of the cabinet, this handle being adjacent one side wall 3 of the cabinet, as for instance the right side wall, and being movable in a plane parallel therewith. As illustrated there is a switch operating spindle having a cranked portion 15 which extends into slots 16 formed in the insulating elements 14 of the switching members. The spindle is mounted in bearing apertures in the side walls 3 of the cabinet and it terminates in a handle 17 movable as already described in a plane parallel with the adjacent side wall of the cabinet. When the handle 17 is in the position shown by full lines in Figs. 1, 2 and 5 the switch is in closed position. When the handle is moved to the position shown in Fig. 3 and shown by dot-and-dash lines in Fig. 2 the switch is in open position. Preferably a stop device 18 is provided for limiting the movement of the handle 17 and for preventing lateral distortion of the said handle.

In order to normally close the opening 7 in the front wall of the cabinet so as to prevent access therethrough to the fuse contacts, there is provided a movable auxiliary cover 19 which is parallel with the main cover. The auxiliary cover 19 is guided for movement in parallelism with the main cover laterally from its normal position in which it covers the opening 7. This lateral movement unlocks the auxiliary cover and it is then movable vertically to an open position in which the opening 7 is uncovered. There is provided an interlocking means which serves to prevent bodily movement of the cover out of its first or locked position when the handle 17 is in its switch closing position and which also serves to prevent movement of the handle out of its switch opening position when the cover 17 is in its second or unlocked position.

Preferably the interlocking means is in the form of a laterally movable slide 20 on the main cover having a normal position in which it is directly obstructed by the switch handle 17 when the latter is in switch closing position and having a laterally projecting position in which it directly obstructs the handle against switch closing movement. The slide 20 is preferably a flat plate parallel with the main cover and movable rectilinearly relatively thereto. The slide is held in place on the main cover and is guided by means of upper and lower horizontal guides. The upper guide comprises a rear bar 21 and a wider front strip 22, and the lower guide comprises a rear bar 23 and a wider front strip 24. The slide 20 has an opening 25 therein which is of approximately the same size as the opening 7 in the main cover and which is adapted to register or approxi-

mately register with the said opening 7 when the slide is in its laterally projecting position.

The auxiliary cover 19 is connected with the slide 20 so as to move laterally therewith, but it is nevertheless free to move in another direction, ordinarily vertically, with respect thereto when the slide is in its laterally projecting position. The cover 19 is preferably a flat plate located between the slide 20 and the main cover 5 and when it is so constructed and located the said slide is provided with vertical guides 26 and 27 which engage the cover 19 at the sides thereof to guide it for vertical rectilinear movement. The guides 26 and 27 may be thin flat strips of the same thickness as the cover 19 and they may be secured to the rear face of the slide 20 by spot welding or otherwise. In addition to the strips 26 and 27, there may be provided a third strip 28 which serves as a spacing member between the right portion of the slide and the corresponding portion of the front cover 5.

The rear bar 23 of the lower horizontal guide is divided into two parts 23^a and 23^b and between the said parts there is provided a space of the proper width to permit the cover 19 to move vertically downward. The cover 19 is notched at 19^a, and when the cover and slide are in their normal positions as shown in Fig. 1 the portion of the cover above the notch 19^a fits between the two horizontal guides and the portion of the cover at the right of the notch extends into the opening between the bars 23^a and 23^b. When the parts are in these positions the switch handle 17 is free to be moved to its switch closing position as shown. With the handle in switch closing position the movement of the slide toward the right is prevented and the auxiliary cover 19 is locked in its closed position by reason of its engagement with the bar 23^a.

When the switch handle 17 is moved to its lower switch opening position as shown in Fig. 3 the slide 20 is free to be moved to its projecting position as shown in the said figure. This brings the opening 25 into register with the opening 7. The auxiliary cover 19 is held between the two guide strips 26 and 27 and is therefore moved toward the right to a position in vertical register with the opening between the ends of the two bars 23^a and 23^b. The cover may then be moved vertically downward to the position shown in Fig. 3, thus uncovering the opening 7 and permitting access to the fuses held by the contacts 9, 9. This downward movement may take place automatically by gravity, or it may be controlled manually by means of a knob 29 secured to the cover 19 near the top thereof. With the parts in the positions shown in Fig. 3 it will be apparent that the switch handle 17 is locked against switch

closing movement and that the auxiliary cover 19, by reason of its position between the bars 23^a and 23^b prevents lateral movement of the slide 20. When the auxiliary cover 19 is moved to its upper position by means of the knob 29 the cover and slide can then be moved laterally toward the left and restored to their normal positions as shown in Fig. 1. Then the handle 17 is free to be moved to its switch closing position.

What I claim is:

1. In an inclosed fused switch, the combination of a cabinet having an openable main cover with an opening therein, fuse contacts and a switch within the cabinet respectively accessible and inaccessible through the said opening when the cover is closed, a switch operating handle adjacent one side wall of the cabinet and movable in a plane parallel therewith, a movable auxiliary cover parallel with the main cover and normally covering the opening therein, means for guiding the auxiliary cover for movement in parallelism with the plane of the main cover laterally from its said normal position and then vertically to an open position, and means interlocking with the handle for preventing the said lateral movement of the auxiliary cover when the handle is in switch closing position and for preventing switch closing movement of the handle when the auxiliary cover has been moved laterally.

2. In an inclosed fused switch, the combination of a cabinet having an openable main cover with an opening therein, fuse contacts and a switch within the cabinet respectively accessible and inaccessible through the said opening when the cover is closed, a switch operating handle adjacent one side wall of the cabinet and movable in a plane parallel therewith, a laterally movable slide on the cover having a normal position in which it is directly obstructed by the handle when in switch closing position and having a laterally projecting position in which it directly obstructs the handle against switch closing movement, an auxiliary cover for the main cover opening movable laterally with the said slide and movable independently thereof to an open position when the slide is in its said projecting position, the last said movement being in parallelism with the plane of the main cover, and means on the main cover interlocking with the auxiliary cover to hold it in closed position when the slide is in its normal position and to prevent lateral movement of the said auxiliary cover and the slide when the said cover is in its said open position.

3. An inclosed fused switch as set forth in claim 2, wherein the independent movement of the auxiliary cover is vertical.

4. An inclosed fused switch as set forth in claim 2, wherein the slide is horizontally movable rectilinearly under the control of horizontal guides on the main cover and

wherein the auxiliary cover is vertically movable rectilinearly under the control of vertical guides on the slide.

5. An inclosed fused switch as set forth in claim 2, wherein the auxiliary cover is between the main cover and the slide and is guided for rectilinear movement with respect to the latter.

In testimony whereof I have hereunto set my hand this 9th day of Jan., 1931.
